UNITED STATES PATENT OFFICE.

HOMER C. SNOOK, OF SOUTH ORANGE, NEW JERSEY, ASSIGNOR TO WESTERN ELECTRIC COMPANY, INCORPORATED, OF NEW YORK, N. Y., A CORPORATION OF NEW YORK.

OSCILLATION GENERATOR.

Application filed June 8, 1922. Serial No. 566,724.

To all whom it may concern:

Be it known that I, HOMER C. SNOOK, a citizen of the United States of America, residing at South Orange, in the county of 5 Essex and State of New Jersey, have invented certain new and useful Improvements in Oscillation Generators, of which the following is a full, clear, concise, and exact description.

- 10 This invention relates to a method of and means for generating electric oscillations. Briefly described one apparatus for practicing the present invention comprises an electric discharge device having main electrodes between which an electron stream is adapted to be established and auxiliary electrodes between which an electron stream may be produced and controlled by a tuned 15 circuit. Some of the electrons of the auxiliary stream are permitted to discharge into the space between the main electrodes to set up an electrical field or charge-in-space for controlling the main electron stream synchronously with the oscillating current 20 flowing in the tuned circuit.

One object of the present invention is the provision of means whereby a charge-in-space may be used to control the space current flow between the electrodes of an 30 electron discharge device. Another object is the provision of means whereby the control charge-in-space may be caused to vary synchronously with an oscillating current whereby sustained oscillations may be generated.

35 These objects and others which appear as the nature of the invention is set forth may be accomplished by means of the arrangement shown in the drawing, the single figure 40 of which illustrates a circuit for practicing this invention.

In this figure the evacuated vessel 1 includes main electrodes, namely a cathode 2 and an anode 3, and auxiliary electrodes, 45 viz, a cathode 4, an anode 5 and a control element or grid 6. The anode 5 is provided with perforations 5a. Heating current is supplied to the cathode 2 by the source 7 and to the cathode 4 by the source 8. Potential is supplied to the main anode 3 by the source 9 and to the auxiliary anode 5 by the source 10. Space current from the 50 battery 9 flows through the coil 11 which is coupled to the coil 12 shunted by the condenser 13 to constitute a tuned frequency

determining circuit. The coil 12 and condenser 13 may both be adjustable as indicated by the arrows and by adjusting either the condenser or coil, or both, the constants of the tuned circuit and hence the frequency 60 of the current generated may be changed.

Coupled to the coil 12 is a second coil 14 which is included in the input circuit connecting the cathode 4 and grid 6 of the auxiliary discharge path, whereby the space 65 current discharge to the anode 5 may be controlled. The position of the anode 5 and the voltages of the sources 10 and 9 should be so related, that the electrons emitted by the cathode 4 will be attracted to the anode 70 5 rather than directly to the anode 3. Some electrons emitted by the cathode 4 will be discharged upon the solid portions of the anode 5, while others will pass through the 75 perforations provided therein and establish an electric field in the space between the main electrodes 2 and 3.

Under operating conditions, oscillations set up in the tuned circuit will react through the coupling 12-14 and impress a fluctuating potential of a frequency determined by the constants of the tuned circuit 12-13 upon the grid 6. This in turn causes the space current between the electrodes 4 and 80 5 and also the number of electrons discharged from the auxiliary cathode 4 into the space between the main electrodes 2 and 3 to vary synchronously with this control potential. An electrical field which varies 85 in accordance with the oscillations generated in the tuned circuit will, therefore, be produced in the space path between the main electrodes to control the flow of current therebetween and if the coupling of coils 11 and 12 is such as to enable the change 90 95 in current in coil 11 to induce an aiding electromotive force in coil 12 energy will be supplied to the tuned circuit to maintain the flow of oscillatory current in it. A load 100 circuit may be connected to the oscillatory circuit at the terminals 15.

From the preceding description it will be apparent that a characteristic feature of this invention resides in the use of a varying charge-in-space, which is caused to fluctuate 105 synchronously with variations produced in a tuned circuit, to control the flow of space current between the cathode and anode of an electron discharge device.

In passing it is noted that the arrange- 110

ment described above may be used as an amplifier. By supplying the waves to be amplified to the coil 14 current variations of increased amplitude will flow through 5 the coil 11, to which a circuit of utilization may be coupled.

Although a particular circuit arrangement and certain specific apparatus have been described with the object of completely and 10 clearly disclosing the principles of the invention, it is to be understood that this invention is not to be limited to the arrangement described, but only by the scope of the appended claims.

15 What is claimed is.

1. A method of generating oscillations by means of an arrangement including an electron discharge device which comprises establishing a space discharge within the device, 20 projecting a stream of electrons into said discharge and cyclically varying the intensity of said electron stream.

2. A method of generating oscillations by means of an arrangement including an electric discharge device which comprises establishing a space discharge within the device, using energy from said discharge to produce oscillations, projecting a stream of electrons into said space discharge and controlling the intensity of said electron stream by said oscillations.

3. An oscillation generator comprising an electric discharge device, means for producing a space discharge within said device, 35 means for projecting a stream of electrons into said space discharge and means for controlling the intensity of said electron stream.

4. An oscillation generator comprising an electric discharge device, means for producing a space discharge within said device, means for using energy from said space discharge to produce oscillations, means for projecting a stream of electrons into said space discharge and means for controlling the intensity of said electron stream in response to the produced oscillations.

5. An oscillation generator comprising an electric discharge device, means for producing a space discharge within said device, an external circuit for said discharge, a tuned circuit coupled to said external circuit, means for projecting a stream of electrons into said space discharge and a control circuit for said electron stream, said control circuit being coupled to said tuned circuit.

6. An oscillation generator comprising an

electric discharge device, means for producing an electric discharge within the device, an external path for said discharge, a tuned circuit associated with said path, means for producing an auxiliary discharge within said device, a control element for said auxiliary discharge, means coupled to 60 said tuned circuit for impressing a cyclically varying potential upon said control element and means whereby said first mentioned discharge is controlled solely by the field produced by the auxiliary discharge. 70

7. An oscillation generator comprising an electric discharge device, means for producing a space discharge within the device, means for producing a second space discharge within said device, an external circuit for said first discharge and a control circuit for said second discharge path, a tuned circuit coupled to said external circuit and said control circuit, and means whereby the first mentioned discharge is controlled solely by the field produced by said second discharge.

8. An oscillation generator comprising an electric discharge device having discharge electrodes and auxiliary electrodes including a control element, means for producing a discharge between said first mentioned electrodes, means for producing a discharge between said auxiliary electrodes, a tuned circuit associated with the first mentioned discharge producing means designed to impress an oscillating potential upon said control element and means whereby the discharge between the first mentioned electrodes is controlled solely by the field produced by the discharge between said auxiliary electrodes.

9. An oscillation generator comprising an electric discharge device, a main cathode and anode in said device, an auxiliary cathode and anode in said device, said auxiliary anode being perforated and the space current path of said first cathode and anode being at an angle to the space current path of said second cathode and anode, an external connection between said first anode and cathode, a tuned circuit associated with said connection, a control electrode between said second anode and cathode, means coupled to said tuned circuit for impressing a cyclically varying potential upon said control electrode, and an external connection between said second cathode and anode.

In witness whereof, I hereunto subscribe my name this 7th day of June A. D., 1922.

HOMER C. SNOOK,
